His Attorneys.

UNITED STATES PATENT OFFICE.

CHARLES M. KRUGER, OF OVERLAND, MISSOURI.

LIQUID-DISPENSING DEVICE.

Application filed September 24, 1925. Serial No. 58,299.

This invention relates to improvements in liquid dispensing device and consists in the novel construction hereinafter disclosed.

An object of the invention is to provide in connection with a container, a top therefore equipped with a pouring spout and having arranged in connection therewith a vent opening that is protected against the admission of dirt or moisture and which will operate to prevent the liquid from splashing from the container when poured therefrom.

Another object of the invention is to provide a dispensing device for liquids having means for venting the container whereby the container may be filled through the pouring spout and the liquid discharged from the pouring spout in such a way that the air will escape from the container both on the filling and pouring operation.

Additional advantages of the structure will be apparent from the following detailed description thereof taken in connection with the accompanying drawing in which

Fig. 1 is an elevation of the device.

Fig. 2 is a vertical section through a portion of the device showing the arrangement of the top and pouring spout in relation to the container, and,

Fig. 3 is a bottom plan view of the top with the sealing gasket removed.

In the embodiment of the invention illustrated in the drawing, the container is shown as comprising a jar 1 preferably of the well known type commonly used as a fruit jar and having an exteriorly threaded opening 2 at the top, and arranged for threaded engagement with the jar is a cap 3 including a threaded lower section 4 that threads over the portion 2 of the jar, a horizontal portion 5 that extends parallel with the upper edge of the jar and a dome-shaped section 6 that has a central opening 45 with a vertical flange 7 encircling the opening.

The pouring spout 8 formed of a rolled sheet of metal and having an upward taper, the ends of the metal being pressed together to form a seam 9 and the upper edge of the spout being beveled to form a pouring outlet 10, extends through the cap, the flange 7 embracing and impinging against the side wall of the spout to which it is secured either by soldering or, if desired, by rolling or other convenient means of fastening the

two parts together. The spout extends downwardly from the top wall of the cap and has a flared portion forming a flange 11. A bent plate having an inclined upper wall 12, a horizontal flange section 13 and a vertical flange 14, fits over the spout so that the flange 11 abuts against the lower edge of the opening formed by the flange 14 and is connected therewith by crimping, soldering or other convenient means of attachment.

It will be noted that the plate forms a partition wall which, with the dome portion 6 of the cap, comprises a chamber. In order to admit the passage of air into and out of the container during the filling and pouring operation from the device, a vent opening is formed through both walls of the cap. In the edge of the flange 13 and opposite the pouring side of the pouring opening, there is formed a semi-elliptical cut out portion 15. In mounting the cap on the container, a gasket or sealing ring 16 is interposed between the top edge of the container and the lower face of the wall 5 of the cap. The width of the ring 16 is such that it extends inwardly of the opening 15 so that it constitutes a protection or baffle to prevent the contents of the jar from splashing through the opening 15 when the contents is being poured from the container; but a sufficient space between the inner edge of the ring 16 and the edge of the opening 15 remains so that there will be a free passage of the air to and from the container.

Directly above the opening 15 is a perforation 17 through the wall of the dome section 6 of the cap, and the metal below the perforation 17 is deflected inwardly to form a channelled surface 18 for the admission and exit of air to and from the chamber formed between the upper and lower walls of the cap. The overhanging edge of the perforation 17 constitutes a shield for the opening through the channel 18 so as to prevent the admission of moisture, dirt or any other foreign substance into the chamber between the walls of the cap.

The device is primarily designed for dispensing measured quantities of lubricating oil and it will be understood that it may be conveniently filled from a lubricating oil pump through the pouring spout, as the accumulated air in the jar will pass outwardly through the opening 15 into the chamber in the cap and thence to atmosphere through the opening in the upper wall of the cap.

In pouring the contents of the jar, the ring 16 deflects the flow of the oil from the edge of the opening 15 and against the inclined inner surface 12 of the lower wall of the cap, the air passing out into the chamber between the two walls of the cap and then to atmosphere through the opening 17.

The device is so designed that it may be very economically manufactured and so that 10 it will be strong and durable in use. I am aware that the invention may be modified in certain particulars without departing from the spirit and scope thereof.

I do not limit myself therefore to unessential details, but what I claim and desire to secure by Letters Patent is:—

- 15 1. In a liquid dispensing device, the combination with a container, of a cap, a spout connected with said cap and said cap being formed from spaced walls and the lower wall comprising a funnel shaped member connected with the lower end of the spout and having a vent opening therein communicating with the opening of the container and the upper wall having a slit therein, a portion of said upper wall immediately adjacent and beneath said slit being bent inwardly forming a trough shaped baffle.
- 20 2. In a liquid dispensing device, the combination with a container, of a cap formed from spaced walls, the lower wall having a

horizontal portion with a vent opening communicating with the opening in the container, and the upper wall of said cap having a vent opening therein, and a gasket between the cap and the upper edge of the container, said gasket extending inwardly of the marginal edge of the cap and across the lower vent opening in a plane slightly 40 therebeneath, thereby constituting a baffle to deflect the liquid from the vent opening formed in the horizontal portion of the lower wall of the cap.

- 25 3. In a liquid dispensing device, the combination with a container, of a cap formed from spaced walls, the lower wall of which has an upwardly deflected portion and a horizontal portion, the upper and lower walls of the cap being provided with aligned central openings, a spout extending through said aligned openings in the cap, and having a flange abutting against the marginal edge of the opening in the lower wall of the cap, and the horizontal portion of the lower wall 50 of the cap having a vent opening in its outer edge, and the upper wall of the cap having a vent opening therein, and a sealing ring interposed between the cap and the opening of the container, said ring extending across the area of the lower vent opening in a plane slightly 55 therebeneath, thereby providing a baffle for said vent opening.

CHARLES M. KRUGER.
